UNITED STATES PATENT OFFICE.

ARTHUR S. LEVY, OF CHICAGO, ILLINOIS.

PROCESS AND APPARATUS FOR THE STANDARDIZED FINISHING OF INTERCHANGEABLE ARTIFICIAL TEETH.

Application filed July 29, 1925. Serial No. 46,884.

My present invention relates to the manufacture of artificial teeth and more particularly to the production of standardized interchangeable facings.

The standardization of interchangeable facings is difficult to accomplish because there is marked variation in the structure of the baked facings due to various shrinkage in the molds and to wear of the molds and as the facings are quite small and must be finished to extreme accuracy, it is at once apparent that exact standardization is quite difficult to attain. After many years of careful experimentation with various processes and mechanism for producing a standardized interchangeable facing, I have discovered that the most satisfactory was based on the selection of the surface of the pin hole adjacent to a cusp seat as the critical point from which to base all adjustment and finished treatment of the facing. To this end my process contemplates mounting the facing upon a pin in a mounting device, applying pressure on a cusp seat to set it parallel with a predetermined plane and hold the pin pressed against the adjacent surface of the pin hole, and, with the facing thus held, it is presented in predetermined position to a portable holder or jig with which it moves from one to another of the finishing machines until completed. It will thus be seen that the facing being mounted in predetermined position on the holder and such position being always fixed with reference to the upper surface of its pin hole, it follows that all of the finished facings will be exactly standardized with relation to this surface of the pin hole, and it follows that all facings so manufactured can be readily interchanged because the distance between the cusp face which will receive the slotted cusp seat and the adjacent edge of the mounting pin will always be the same.

More particularly, my invention is concerned with the designing of a fixture which is adapted to mount in portable holders artificial root facings of the type forming the subject matter of my pending application, Serial No. 584,729, wherein is shown an integral homogeneous porcelain facing having a root extension and angled backing seats in at least one of which is provided an undercut keyhole slot for the reception of the mounting pin.

In an artificial tooth of this character it

is of vital importance that the unfinished porcelain tooth shall at all times be set in the holder with the faces to be ground in an exact predetermined relation to the top surface of the pin hole. When the teeth are thus accurately positioned in the holders by the utilization of my improved mounting device the holders can be mounted successively in the several finishing machines and the tooth ground and finished to an exact standard which is of greatest importance in connection with the interchangeability of the tooth, it being obvious that unless the cusp seats of the finished tooth, which is to replace another, have the identical spacing from the backing pin that the corresponding seats had in the tooth that has been removed, such replacement tooth could not be mounted correctly in the mouth.

More particularly my invention contemplates the utilization of a base adapted to receive the holders one at a time and a frame having a pin corresponding to the mounting pin for the tooth and disposed parallel with assembling guide surfaces in the base so that the frame with the tooth mounted thereon will slide into the frame in the direction of the axis of the mounting pin. In addition to this the frame carries conveniently operable means engaging a cusp seat of a tooth mounted on the pin so as to force the upper wall of the slot against the pin and to dispose the slotted cusp seat always in or parallel with the same plane.

My invention also comprises the novel details of construction in the portable tooth holder itself and in the manner of mounting same in the base and in the detail structure of the tooth carrying frame and the means for guiding the same into exact assembled relation with the base to mount the tooth in the holder.

My invention further comprises the novel details of construction and arrangements of parts, which are hereinafter more particularly described and claimed, and which are illustrated in their preferred embodiments only in the accompanying drawings which form a part of this specification, and in which:

Fig. 1 is a side elevation of the mounting device showing the tooth carrying frame detached in dotted lines and assembled on the base in full lines, the artificial tooth being shown in dotted lines only in relation to the assembled device.

Fig. 2 is a top plan view of the assembled device shown in Fig. 1.

Fig. 3 is a plan view of the base; and

Fig. 4 is a bottom view of the tooth carrying frame.

Fig. 5 is a view partly in cross section of one of the portable holders showing the tooth in cross section in its relation to the co-acting elements on the carrier which, by 10 engaging the tooth, set it always into an exact standardized position in the holder.

Fig. 6 is a plan view of a holder with a tooth mounted therein and the wax or other mounting substance cut away so as to expose 15 the cusp seats of the tooth to be ground.

Fig. 7 is a cross-sectional view of the frame in which the tooth centering pin is arranged to move axially.

Fig. 8 is a side elevation of Fig. 7.

Fig. 9 is a plan view of Fig. 7.

Fig. 10 is an enlarged detail view of a shouldered mounting pin for the tooth on the carrier frame.

Fig. 11 is a bottom view of Fig. 7 with 25 a modified means for adjusting the pin carrying slide.

Similar reference numerals refer to similar parts throughout the drawings.

In the embodiment of my invention illustrated in Figs. 1 to 6, I show a mechanism for carrying my process into effect, comprising a mounting device having a suitable base 1 with a pair of spaced raised shoulders 2 at one end and a spaced transverse shoulder 3 on the other end, and I drill or otherwise form in this base four holes 5, 6, 7 and 8, all of which are made parallel, the holes 5 and 6 being formed in the offset shoulder 10 provided at the base 40 of a bevelled face leading from the shoulder 3 to the end of the base. The sloping surfaces 9 terminate in vertical shoulders 11 parallel with the opposed face of the transverse shoulder 3 and spaced therefrom to form a flat seat 13 having bevelled side surfaces 12. In the center of the seat I drill a counterbored socket 14 adapted to receive freely the shank 15 of the portable tooth holders or jigs 16. Each tooth holder is provided with parallel vertical faces adapted to fit snugly between the shoulders 3 and 11 and it preferably has the axis of its shank 15 slightly closer to the shoulder 3 than to the shoulder 11 so that it can only be mounted in one way in the base. Between the shoulders 2 I mount a vertically disposed spring 17 which snaps over the adjacent side of a holder 16 and presses it against the shoulder 3. The holder has a top recess 18 adapted to receive wax, plaster or any equivalent material 19 in which an artificial tooth 20 can be mounted and set in the holder.

That part of the device which I term the carrier, since it is utilized to present the

teeth to the plastic material in the holders and mount them therein, comprises a back plate 21 having mounted thereon, between undercut side guides 22 and 23, a longitudinally adjustable slide bar 24, having its side edges bevelled. The bar at one end has secured thereto a screw 25 having a jamb nut 26 which engages a shoulder 27 provided with an aperture through which the screw projects. A jamb nut 28 is applied on the screw on the opposite side of the shoulder 27 and the nuts permit the block to be adjusted accurately to the desired position in the carrier. The shoulder 27 is integral with a plate 29 attached to the top of the back plate 21 and projecting far enough beyond same to protect the outer end of the screw 25. I mount rigidly on the slide block 24 a post 30 having concentric therewith a pin 31 which is adapted to enter the pin hole 32 which is molded in the tooth 20 with its axis parallel with the cusp seat 34. Usually this hole connects with a slot 33 cut through the seat 34.

I hingedly mount a spring-pressed clamp 36, by means of a pin 35 on the slide 24, the clamp having one end 37 serving as a handle and the other end terminating in the finger 38 (see Fig. 5) which has a bevelled face 39 terminating in a straight edge 40 disposed transversely of the carriage and parallel with the plate 21 and adapted to engage, with a transverse line contact the intermediate transverse portion of the cusp seat 34 of the artificial tooth 20 when mounted on the pin 31. This edge 40 stands at right angles to the axis of the pin 31 and will stand substantially midway between the shoulders formed on this pin by cutting away its intermediate portion at 31^a, see Fig. 10. This provides a three point contact between pin and clamp and the tooth. This arrangement will best take care of any possible irregularities in the baking of the tooth and it causes the clamp to set the tooth with the pin 31 in contact with the upper portion of the pin hole 32 and the tooth held against opening about the pin. I provide the frame with four mounting posts 41 and 42 having reduced ends 43 adapted to be forced respectively in the base holes 5 and 6. The frame at its other end has posts 44 and 45 whose reduced ends 43 are adapted to be received respectively in the holes 7 and 8 of the base. The reduced ends 43 are longer than the pin 31 and the base has its bevelled face 10 cut away at 46 to clear the screw 25 of the frame when the parts are assembled. The clamp 37 is controlled by a coil spring 47 interposed between its handle portion 37 and the back plate 21 of the frame.

In the operation of my process with the device as thus far described, the frame is detached from the base, the clamp is pressed away from the pin 31 and an artificial tooth 130

20 is mounted on the pin by inserting the latter into the pin hole 32 in the tooth. The clamp is then released and its edge 40, by engaging the cusp seat 34 of the tooth, will force the latter against the pin so that the shouldered edge of the pin will contact with the upper wall of the pin hole 32 and the tooth will be held in this position against rocking about the pin. One of the holders 16 is then provided with suitable plastic material in its recess 18 and is mounted between the shoulders 11 and 3 on the base and held in place by the spring 17. The frame is then inverted and its pins are caused to enter the holes 5, 6, 7 and 8 in the base, in doing which the artificial tooth is caused to be pressed down into the plastic material in the holder, as shown in Fig. 5, and is thus set in the correct standardized position in the holder and remains there until the plastic material hardens sufficiently to set it, after which the clamp is released and the frame slipped away from the base, leaving the tooth embedded in the plastic material in the holder as in a jig. In this manner the teeth are accurately and quickly set in the holders and after the surplus plastic material has been removed to expose fully the tooth's cusp seats, the holders can be transferred to the various finishing machines, all of which will work with perfect standardization to grind the cusp seats 34 and 48 and finish the tooth.

In the modification of my carrier frame shown in Figs. 7 to 9, the back plate 21 is provided opposite the slide bar 24 with a raised shoulder 49 having a hole bored therethrough with its axis parallel with the adjacent face of the plate 21 and adapted to receive a slide pin 50 having a finger portion 51 with a straight edge 40, as shown in Fig. 5. A spring 52, acting to press this pin towards the center of the tooth mounting pin 31, is seated against a bracket 53 attached to the outer end of the shoulder 49 which is undercut to provide a slot 55^a in which a bell crank lever 54 is pivotally mounted with its upper end working through a slot 55 and engaging the pin 50 and its lower end provided with an elongated slot 56 which receives a transverse adjustable wedge 57. This wedge, as shown more clearly in Fig. 9, is carried by a laterally movable spring-pressed pin 58 having at its outer end a finger grip 59, between which and the plate is interposed a spring 60. A fixed opposed grip finger 59^a is provided. The pin 58 is longitudinally slotted and is held in position by a pin 61 working through the slot. By this arrangement the grasping of the frame will force the wedge inwardly.

To simplify the adjustment means for the slide bar 24 I show in Fig. 11 a modified arrangement wherein the slide bar is provided with a diagonal bore 62 opening

through its sides and disposed to provide parallel wedge faces 66 and 67. Through the side guides 22 and 23 I insert screw pins 65 having their inner ends 64 tapered and adapted to engage the wedge faces 66 and 67 respectively of the bore 62. In this way by turning the screws reversely the slide can be moved in either direction desired with an extremely delicate adjustment and locked securely in place.

The process permits quick and accurate mounting of the teeth in the holders in such manner that they can be finished rapidly by a series of operations which are all free of any individual adjustments for each tooth.

Though I have described with great particularly the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. An improvement in the art of standardizing interchangeable facings having a pin securing hole with its axis in predetermined relation to a cusp seat, which consists in mounting said facing on a pin inserted in said hole, forcing the wall of the pin hole that is adjacent to the cusp seat against the pin, holding the facing on the pin with its cusp seat parallel with a given plane, setting the facing so positioned in a standardized transfer carrier, removing the facing with the carrier to a standardized mounting on a grinding machine, and grinding the cusp seat parallel with said plane to leave a predetermined standard thickness between the finished seat and said wall of the pin hole.

2. An improvement in the art of standardizing interchangeable facings having a pin securing hole with its axis parallel with a cusp seat, which consists in mounting said facing on a pin in said hole, forcing the wall of the pin hole that is adjacent to the cusp seat against the pin, holding the facing on the pin with its cusp seat parallel with a given plane, mounting the facing so held in predetermined position in a standard holder by plastic means, and transporting said holder through facing finishing machines having their working elements set in predetermined relationship to the holder as it is presented thereto.

3. In a mounting fixture for artificial teeth, a base, means to mount therein, in predetermined position, a tooth holder containing plastic material, and means to present a tooth in predetermined relation to said holder and mount it in the plastic material thereof, said latter means comprising

ing a pin adapted to enter the pin hole in the tooth, and co-acting means to press the cusp seat towards said pin.

4. In a mounting fixture for artificial teeth each having a pin hole and a cusp seat, a base, means to mount therein, in predetermined position, a tooth holder containing plastic material, means to present a tooth in predetermined relation to said holder and 10 mount it in the plastic material thereof, said latter means comprising a pin adapted to enter the pin hole in the tooth, and means engaging the tooth to hold it in predetermined position by causing said pin to 15 press against the wall of the pin hole adjacent to the cusp seat.

5. In a mounting fixture for artificial teeth, a base, a demountable tooth holder containing plastic material adapted to receive and hold a tooth when pressed thereinto, means for mounting the tooth holder in the base in a predetermined standardized position, means comprising a pin and presser means adapted to coact with the 25 tooth to hold it in a standardized position in said mounting device, and means to guide the device into a predetermined relation to the holder in the base for pressing the tooth into the plastic material.

30 6. The combination with a base having a seat adapted to receive a removable tooth holder, of a tooth holder having plastic material adapted to receive and hold a tooth when pressed thereinto which has a slotted cusp seat with a pin hole at the bottom of the slot, a tooth mounting device having a rigid pin adapted to enter said hole in said tooth, releasable means to hold said tooth with its cusp seat in a predetermined stand- 35 ardized position relative thereto on said pin, and means to guide the device into a predetermined relation to a holder in said base in which it presents the tooth to said plastic material.

45 7. In a device for mounting artificial teeth having pin holes and cusp seats in holders, a pin adapted to enter the pin hole in the tooth to be mounted, a clamp adapted to engage the tooth's cusp seat and force it against the pin, a support for the pin and clamp, and means to guide said support to present the tooth to a receiving holder.

8. In a device for mounting artificial teeth having pin holes and cusp seats in holders, a shouldered pin adapted to enter the pin hole in the tooth to be mounted, a clamp adapted to engage the tooth's cusp seat between the shoulders of the pin and force it against the pin, a support for the pin and clamp, and means to guide said support to present the tooth to a receiving holder.

9. In a device for mounting artificial teeth having pin holes and cusp seats in holders, a pin adapted to enter the pin hole in the tooth to be mounted, a clamp having a straight edge adapted to engage the tooth's cusp seat on both sides of said pin and force it against the pin, a support for the pin and clamp, and means to guide said support to present the tooth to a receiving holder.

10. In a device for mounting artificial teeth in holders, a base having a seat for the holders, a rounded shank on the holder, 75 a rounded socket on the base to receive the shank, a shoulder on the base, a complementary shoulder on the holder, spring means on the base adapted to press said shoulders into engagement, a tooth carrier 80 having means to mount a tooth in predetermined position thereon which comprise a pin adapted to enter a pin hole in the tooth, means parallel with said pin to guide said carrier into predetermined relation to the 85 base, and plastic material in the holder adapted to receive the tooth from the carrier.

11. In a tooth mounting device, a carrier 90 frame adapted to present teeth in predetermined position to the mounting device, said carrier comprising an adjustable slide, guides for said slide disposed parallel with the axis of the pin hole in a tooth mounted on the carrier, and releasable mounting elements carried by the slide.

12. A mounting device in accordance with claim 11, in which the releasable mounting elements comprising a pin, and a spring-pressed clamp movable towards the pin into 100 position to hold the tooth in predetermined position on the pin.

13. A device for mounting artificial teeth in holders, comprising a base having a holder receptacle and spring means to clasp the holder in predetermined position therein, fixed holes in said base, a tooth carrier comprising a frame having fixed pins adapted to enter said holes in the base, a pin adapted to enter the hole in an artificial tooth, and a releasable clamp adapted to hold the tooth on said latter pin.

14. The art of grinding artificial teeth having a cusp seat and a pin hole, which consists in setting the tooth for grinding by reference to the wall of the pin hole adjacent to the cusp seat, holding the tooth in said position, and grinding the cusp seat to produce a standardized thickness of material between said wall of the pin hole and the finished seat.

In testimony whereof I affix my signature.

ARTHUR S. LEVY.
